US00D869223S

(12) **United States Design Patent** (10) **Patent No.:** **US D869,223 S**
Kurani et al. (45) **Date of Patent:** **** Dec. 10, 2019**

- (54) **PAN**
- (71) Applicant: **Tekno Products Inc.**, Rutherford, NJ (US)
- (72) Inventors: **Jeff Kurani**, New York, NY (US); **Manoj Budhrani**, Kowloon (HK)
- (73) Assignee: **Tekno Products Inc.**, Rutherford, NJ (US)
- (**) Term: **15 Years**
- (21) Appl. No.: **29/600,138**
- (22) Filed: **Apr. 10, 2017**
- (51) LOC (12) Cl. **07-02**
- (52) U.S. Cl. **USPC D7/361**
- (58) **Field of Classification Search**

(57) **CLAIM**

The ornamental design for a pan, as shown and described.

DESCRIPTION

FIG. 1 is a top, rear and right-side perspective view of a pan, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top view thereof; and,

FIG. 7 is a bottom view thereof.

The broken lines shown in the drawings depict portions of the pan that form no part of the claimed design.

1 Claim, 6 Drawing Sheets
